J. C. DILL

GRAIN STOWAGE DEVICE

Filed April 7, 1926

UNITED STATES PATENT OFFICE.

JOHN CROMIE DILL, OF VANCOUVER, BRITISH COLUMBIA, CANADA.

GRAIN-STOWAGE DEVICE.

Application filed April 7, 1926, Serial No. 100,388, and in Canada May 19, 1925.

My invention relates to improvements in grain stowage devices the objects of which are to provide means whereby grain fed by spout into a ship's hold may be conveyed to remote portions of the hold without having recourse to manual labour. A further object is to permit the introduction of air at atmospheric pressure with the grain to the distributor head, and a still further object is to provide means whereby the point of entry of the grain to the distributor head may be varied and the flow of air thereto may be regulated.

The invention consists essentially of a distributor head having one or more delivery nozzles and an equal number of feed openings, a duct for admitting air to the head and a fan rotatable therein for receiving the grain and for discharging it through the delivery nozzles, as will be more fully described in the following specification, in which:—

Fig. 1 is a plan view of my invention.

Fig. 2 is a part sectional view.

Fig. 3 is a fragmentary view of the feed adjusting mechanism.

In the drawings like characters of reference indicate corresponding parts in each figure.

The numeral 1 indicates a base having vertical supports 2 carrying a plurality of frame members 3 which are provided at their outer ends with shackles 4, which serve as a means for suspending the device from suitable cables 5. Upon the frame members 3 a distributor head 6 having side walls 7 is carried, which is provided with one or more nozzles 8 extending horizontally therefrom through which the grain is projected. A blower fan generally indicated by the numeral 9 is rotatably mounted within the head 6, which fan is provided with a plurality of vanes 10 vertically disposed upon a circular plate 11. The vanes of the fan are disposed radially about a central space or core 12 and are preferably connected together at their upper edges by an annular ring 13 which serves as a means of strengthening the fan and may also be utilized in conjunction with a ball bearing (not shown) for journaling the upper end of the fan to the cover plate 19. The fan 9 is mounted upon a shaft 14 which is suitably journalled as at 15 to a supporting member 16 extending between the frame members 3, the lower end of the shaft 14 be-

ing coupled as at 17 to the shaft of a motor 18 carried upon the base 1.

The numeral 19 indicates a cover plate for the distributor head 6 having a depending rim 20 which is adapted to embrace the upper edges of the side walls 7. A shaft 21 having a hand wheel 22 at one end and a worm 23 at the opposite end is journalled upon a bracket 24 mounted upon the side wall 7 of the head and a curved rack 25 is secured to the rim 20 of the cover plate 19 so that by turning the shaft 21 the cover plate 19 may be rotated about the distributor head when desired.

The numeral 26 indicates an air duct concentrically disposed upon the cover plate 6 having a damper 27 which is adapted to control the passage therethrough, the damper being mounted upon a cranked shaft 28 and actuated by a rod 29 which is notched on the underside as at 30 to engage an adjusting stop 31. The numeral 32 indicates a grain spout leading from a suitable source of supply which is connected to an inverted Y 33 having as many legs 34 as there are discharge delivery nozzles 8 to the distributor head. Each of these legs communicate therewith through an aperture 35 in the cover plate 19 which is disposed in close proximity to the centre of the cover, so that the grain entering therethrough is received by the portion of the vanes 10 of the fan 9 which is subject to the lowest velocity.

Having thus described the several parts of my invention I will now briefly explain its use.

The device is adjusted as to position that the delivery nozzles are pointing in the desired direction, the motor is started causing the fan 9 to rotate, grain is then fed through the spout 32 and is allowed to fall through the apertures 35 when it is received by the fan vanes and by centrifugal force is thrown tangentially from the distributor head 6 and through the delivery nozzles to the desired position in the ship's hold.

During the outward throw of the grain by the vanes 10 the damper 27 is adjusted to admit of a suitable flow of air to enter the head through the inlet 26 and the core 12 to prevent the choking effect to the outward grain movement, which would otherwise result from the rarefied air condition due to the increased cross sectional area between the vanes adjacent the periphery of the fan over

the area between the vanes adjacent the core.

If it is found that a portion of the grain fed through an aperture 35 is carried past its corresponding discharge nozzle the cover plate 19 is turned as required against the direction of rotation of the fan, so as to feed the grain through each aperture to the fan vanes at an earlier point and to permit of its total discharge through the proper discharge nozzles.

It will thus be seen that I have invented a grain stowing device through which the flow of grain is supplemented by air to permit of its unrestricted passage between the fan vanes, and through the discharge, whereby the grain may be projected a greater distance than is usual with rotary stowing devices in common use.

What I claim as my invention is:

20 1. A grain stowing device comprising a distributor head having a circumferential outlet and a top inlet, a fan rotatable within said head and provided with a plurality of vanes between which the grain is delivered through the inlet, and means for changing the position of the inlet to vary the setting thereof with respect to the vanes of the fan.

25 2. A grain stowing device comprising a frame, supporting cables attached thereto, vertical supports carried by and depending from said frame, a base secured to the lower ends of said supports, a motor mounted on the base, a drive shaft extending from the

motor upwardly through said frame, a fan comprising a plate fastened to an upper part 35 of the drive shaft and provided with a plurality of spaced vertical vanes radiating from the center of the plate, a casing enclosing said fan and affording a distributing head secured upon the frame, said casing being 40 formed with spaced circumferential outlets, a rotatable closure plate forming the top wall of the casing and provided adjacent the central portion thereof with openings affording inlets to the casing and corresponding in 45 number to the outlets and means for rotating said closure plate to change the angular setting of the inlets with respect to the vanes of the fan.

3. A grain stowing device comprising a 50 casing open at the top and provided with a plurality of spaced circumferential outlets, a plate closing the top of said casing and provided adjacent the center thereof with inlet openings corresponding in number to the outlet openings; a fan rotatably mounted in said casing and presenting a plurality of relatively spaced vertically disposed vanes radiating from a common center, a curved rack carried by said plate, a rotatably journaled 55 worm wheel meshing with said rack and supported from the casing and handle means for rotating said wheel.

Dated at Vancouver, B. C., this 1st day of April, 1926.

JOHN CROMIE DILL.
